CLAIM

The ornamental design for a pet carrier, as shown and described.

DESCRIPTION

FIG. 1 is a front and top perspective view of a pet carrier, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of a portion labeled, ‘FIG. 9’ in FIG. 1;

FIG. 10 is an enlarged view of a portion labeled, ‘FIG. 10’ in FIG. 1;

FIG. 11 is an enlarged view of a portion labeled, ‘FIG. 11’ in FIG. 3; and,

FIG. 12 is an enlarged view of a portion labeled, ‘FIG. 12’ in FIG. 8.

The dash dot dash lines in FIGS. 1, 3, 8, 9, 10, 11 and 12 are for the purpose of depicting the boundary lines and indicators of the enlarged view and form no part of the claimed design.

1 Claim, 12 Drawing Sheets
